attorneys.

L. H. ROGERS, OF BOSTON, MASSACHUSETTS, ASSIGNOR TO HIMSELF AND GEORGE A. ROGERS, OF THE SAME PLACE.

Letters Patent No. 88,077, dated March 23, 1869.

IMPROVED TOILET-MIRROR.

The Schedule referred to in these Letters Patent and making part of the same.

To all whom it may concern:

Be it known that I, L. H. ROGERS, of Boston, in the county of Suffolk, and State of Massachusetts, have invented a new and useful Improvement in Toilet-Mirrors; and I do hereby declare that the following is a full, clear, and exact description thereof, which will enable others skilled in the art to make and use the same, reference being had to the accompanying drawings, forming part of this specification, in which—

Figure 1 represents a front elevation of my improved toilet-mirror.

Figure 2 is a vertical transverse section of the same, taken on the plane of the line $z z$, fig. 1.

Figure 3 is an edge view of the same.

Similar letters of reference indicate corresponding parts.

This invention relates to a new toilet-mirror, of that class in which a portion can be swung out, to reflect, into the main mirror, the reverse of the figure placed between the two; and

The invention consists in a novel manner of connecting the main with the reflecting-mirror, whereby the latter can be swung any desired distance from the main mirror, and turned in any desired direction, or placed above the main mirror, as may be required.

The reflecting-mirror is swivelled to a jointed rod, which can slide in or on a bar, pivoted to the main mirror.

When the bar is in a vertical direction, the rod is let down as far as possible, and the reflecting-mirror will then be held vertically above the main mirror.

When, however, the bar is swung forward, the rod can be drawn out at will, and the reflecting-mirror turned in any desired direction to reflect, into the main mirror, the side or back of the figure placed between them.

A, in the drawing, represents a toilet-mirror of suitable size and form, fitted into a suitable frame, B.

To the top of this frame, is, by a hinge, a , secured

a bar, C, which is slotted or tubular, or provided with guide-straps, to support a sliding, or extension-rod, D, which can be pushed down, as in fig. 2, or drawn out of C, as in fig. 3.

To the outer end of the rod D, is hinged a short plate, E, to which, by means of a swivel-pin, b, the reflecting-mirror F is secured.

The bar C can be swung forward in a horizontal position, as in fig. 3, or inclined, as may be desired.

It may be provided with a suitable device to regulate the degree of inclination. The rod D is then drawn out as far as desired.

The hinge c of the plate E, is so arranged, that the said plate may swing into line with the rod, when the same is swung forward, as shown.

The mirror F is then suspended on the extension-arm C D E, in front of the main mirror A, and can, on the swivel-pin b, be turned in any desired direction.

When the mirror F is not to be especially used, it is placed upon the main mirror, as in figs. 1 and 2.

This is done by pushing the rod D as far as possible into C, when it will reach behind the mirror A, to brace the extension-mirror in the upright position, as in fig. 2.

The plate E is swung forward to suspend the mirror F above A, as is clearly shown in the drawing.

Having thus described my invention, I claim as new, and desire to secure by Letters Patent—

The combination of the hinged bar C, sliding rod D, hinged plate E, and swivel-pin b, for connecting a reflecting-mirror, F, with the main mirror A, all arranged and operating substantially as herein shown and described.

The above specification of my invention signed by me, this 6th day of February, 1869.

L. H. ROGERS.
